GAME APPARATUS

Bruno Radtke, Libertyville, Ill., assignor to The Exhibit Supply Company, Chicago, Ill., a corporation of Illinois

Application April 25, 1935, Serial No. 18,174

5 Claims. (Cl. 273—121)

This invention relates to a game apparatus.

It is an object of this invention to provide an improved game apparatus which is relatively simple and inexpensive in construction and efficient in use.

Another object of the present invention is to provide a game apparatus comprising the combination of: a cabinet including a member providing a ball playing surface and said member having ball-receiving pockets formed therein; a ramp or runway arranged in said cabinet at one side of said playing surface for guiding balls onto said playing surfaces; means for propelling balls one at a time along said ramp or runway so that the same may enter onto said playing surface; a member slidably mounted in said cabinet below said playing surface for temporarily retaining therein balls which enter into said pockets; a ball-stopping member, having the form of a pin, slidably mounted in said cabinet for movement into and out of position to block the passage of a ball from said ramp or runway onto said playing surface; and a member carried by said ball-retaining member for moving said pin into effective position when said ball-retaining member is shifted into position to release balls temporarily held thereby in said pockets.

Other objects will appear hereinafter.

The invention consists in the novel combination and arrangement of parts to be hereinafter described and claimed.

The invention will be best understood by reference to the accompanying drawing, showing the preferred form of construction and in which:

35 Fig. 1 is a perspective view of a game apparatus embodying a preferred form of the present invention;

Fig. 2 is a vertical sectional view on line 2—2 in Fig. 1;

40 Fig. 3 is a sectional view on line 3—3 in Fig. 2; and

Fig. 4 is a sectional view on line 4—4 in Fig. 3.

A game apparatus embodying a preferred form of the present invention is shown in the drawing, is therein generally indicated at 10, and comprises a cabinet 11 which includes an inclined playing board 12 having ball exit openings or pockets 13 therein.

Slidably mounted in the cabinet 11 below the inclined playing board 12 is a ball-retaining member or "shuffle board" 14 in which are provided ball exit openings 15; these exit openings 15 being normally disposed out of registration with the exit openings or pockets 13 so that the

therein balls which enter into the exit openings or pockets 13.

Carried by, and depending from, the ball-retaining members or slide panel 14 is an arm 16 (Fig. 2) and the inner end of the coin slide 17, which is slidably mounted in the cabinet 11, is engageable with this arm 16 so as to move the slide panel 14 (right to left, Fig. 2), and thereby register the ball exit openings 15 in the slide panel 14 with the exit openings or pockets 13 in the inclined playing board 12 and thus discharge the held balls out of the exit openings or pockets 13 onto the inclined runway 18 for return to a point adjacent the elevating device 19.

Provided in the cabinet 11, at one side of the inclined playing board 12, is a ball runway or ramp 20 (Fig. 3) and slidably mounted for vertical movement in the inclined playing board 12 is a ball-stopping member, having the form of a pin 21, the upper end portion 22 of which is movable into and out of effective position in the ramp 20.

Carried by the slide panel 14 is a member 23 which has a substantially horizontally extending end portion or arm 25 and an inclined cam portion 24 that projects under, and bears against, the lower end portion of the ball stop or pin 21.

Operation

When the slide panel 14 is in its normal or initial position, the exit openings 15 therein are disposed out of registration with the exit openings or pockets 13 in the inclined playing board 12 and balls are thus temporarily held in the exit openings or pockets 13 by the slide panel 14.

When the slide panel 14 is in this position the pin 21—22 is disposed in lowered position (Fig. 3), as in dotted lines (Fig. 4) and in this position of the parts the lower end of the pin 21 bears upon the horizontal extension 25 of the cam plate 23—24—25, and the upper end portion 22 of the pin 21 is thus withdrawn out of the ramp or runway 20 so that balls 26 may be projected up the ramp 20, past the pin 21, onto the playing surface 12.

However, when the sliding panel 14 is shifted (right to left, Fig. 2) to register the exit openings 15 therein with the exit openings or pockets 13 in the inclined playing board 12, the inclined cam portion 24 of the cam plate 23—24—25 bears against the lower end of the pin 21 and raises the same into effective position, in the ramp or runway 20, as in full lines, Fig. 4.

When the pin 21—22 is thus disposed in raised or effective position in the ramp or runway 20, it

is impossible to propel balls from the ramp 20 onto the inclined playing surface 12, since any ball propelled up the ramp 20 will engage the ball stopping pin 21-22 and will be prevented 5 thereby from entering onto the playing surface 12; thereby preventing the player from fraudulently playing balls up onto the inclined playing board 12 of the apparatus by operating the plunger 26 while holding the sliding panel 14 and 10 coin slide 17 pressed inwardly.

When the coin slide 17 and slide panel 14 are released for return to their initial positions, the lower end portion of the ball stop or pin 21 rides down the inclined cam surface 24 of the cam 15 plate 23, thereby causing the pin 21 to drop by gravity, and thus retract its upper end portion 22 out of the ball runway or ramp 20 so that balls may again be propelled up the ramp 20 onto the playing surface 12.

20 If a ball is propelled up the ramp or runway when the ball stop or pin 21-22 is in raised position, there is a tendency for the momentum of the ball to cause it to jump over the pin 21-22 and either continue on through the ramp 20 or to jump 25 over onto the playing surface of the inclined playing board 12. To prevent this a strip 27 is extended across the ramp or runway 20 (Figs. 1 and 3) above the ball stop or pin 21 and 22 and in the event a ball is deflected upwardly by 30 engagement with the pin 21-22 it will strike the strip 27 and be prevented by the latter from being deflected out of the ramp or runway 20 onto the playing surface of the inclined playing board 12; it being noted that the strip 27 is so spaced above 35 the pin 21-22 that a ball cannot pass between the strip 27 and the pin 21-22 when the latter is in raised or effective position.

While I have illustrated and described the preferred form of construction for carrying my invention into effect, this is capable of variation and 40 modification, without departing from the spirit of the invention. I, therefore, do not wish to be limited to the precise details of construction set forth, but desire to avail myself of such variations 45 and modifications as come within the scope of the appended claims.

I claim:

1. A game apparatus, comprising the combination of: a cabinet including a member providing 50 a ball playing surface and said member having ball-receiving pockets formed therein; a ramp or runway arranged in said cabinet at one side of said playing surface for guiding balls onto said playing surface; means for propelling balls one at a time along said ramp or runway onto said playing surface so that the same may enter into said pockets; a member slidably mounted in said cabinet below said playing surface for temporarily retaining therein balls which enter into said pockets; a member slidably mounted in said cabinet for movement into and out of position to block the passage of a ball from said ramp or runway onto said 55 playing surface; and a member carried by said second-named and ball-retaining member for moving said third-named and ball-stopping member into effective position when said second-named and ball-retaining member is shifted into position to release balls temporarily held thereby in said pockets.

70 2. A game apparatus, comprising the combination of: a cabinet including a member providing a ball playing surface and said member having ball-receiving pockets therein; a ramp or ball runway arranged in said cabinet at one side of said 75 playing surface for guiding balls onto said playing

surface; means for propelling balls one at a time along said ramp or runway so that the same may enter onto said playing surface; a member slidably mounted in said cabinet below said playing surface for temporarily retaining therein balls which enter into said pockets; a member movable into and out of effective position in said ramp or runway for preventing the passage of balls therefrom onto said playing surface; and means coacting with said second-named and ball-retaining member for moving said third-named member into effective position to prevent the passage of balls from said ramp or runway onto said playing surface when the said second-named and ball-retaining member is moved into ball-releasing position.

3. A game apparatus, comprising the combination of: a cabinet including a member providing a ball playing surface and said member having ball-receiving pockets formed therein; a ramp or runway arranged in said cabinet at one side of said playing surface for guiding balls onto said playing surface; means for propelling balls one at a time along said ramp or runway onto said playing surface so that the same may enter into said pockets; a member slidably mounted in said cabinet below said playing surface for temporarily retaining therein balls which enter into said pockets; a member slidably mounted in said first-named member for movement into and out of position to block the passage of a ball from said ramp or runway onto said playing surface; and means coacting with said second-named and ball-retaining member for moving said third-named member into effective position to block the passage of balls from said ramp or runway onto said playing surface when said second-named and ball-retaining member is shifted into position to release balls temporarily held thereby in said pockets.

4. A game apparatus, comprising the combination of: a cabinet including a member providing a ball playing surface and said member having ball-receiving pockets formed therein; a ramp or ball runway arranged in said cabinet at one side of said playing surface for guiding balls onto said playing surface; means for propelling balls one at a time along said ramp or runway so that the same may enter onto said playing surface; a member slidably mounted in said cabinet below said playing surface for temporarily retaining therein balls which enter into said pockets; a member slidably mounted in said cabinet for movement into and out of position to block the passage of a ball from said ramp or runway onto said playing surface; and means coacting with said ball-retaining member for moving said third-named member into effective position to block the passage of balls from said ramp or runway onto said playing surface when said second-named and ball-retaining member is shifted into position to release balls temporarily held thereby in said pockets.

5. A game apparatus, comprising the combination of: a cabinet including a member providing a ball playing surface and said member having ball-receiving pockets formed therein; a ramp or ball runway arranged in said cabinet at one side of said playing surface for guiding balls onto said playing surface; means for propelling balls one at a time along said ramp or runway so that the same may enter onto said playing surface; a member slidably mounted below said playing surface for temporarily retaining therein balls which enter into said pockets; a member slidably mounted

in said first-named member for movement into and out of position to block the passage of a ball from said ramp or runway onto said playing surface; means coacting with said second-named and ball-retaining member for moving said third-named member into effective position to block the passage of balls from said ramp or runway onto said playing surface when said second-named and

ball-retaining member is shifted into position to release balls temporarily held thereby in said pockets; and a member extended across said ramp or runway above said third-named member and adapted to prevent a ball from jumping over said third-named member or from being deflected thereby out of said ramp or runway. 5

BRUNO RADTKE.
